United States Patent Office

Des. 215,108
Patented Sept. 2, 1969

215,108

CHILD'S VEHICLE

Irwin Cohn, 746 West St., Leominster, Mass. 01453

Filed Nov. 12, 1968, Ser. No. 14,406

Term of patent 3½ years

Int. Cl. D21—02

U.S. Cl. D34—15

FIG. 1

FIG. 2

FIG. 3

FIG. 4

FIG. 1 is a front perspective view of a child's vehicle embodying my new design;

FIG. 2 is a top plan view thereof;

FIG. 3 is a front end view thereof; and

FIG. 4 is a rear end view thereof.

I claim:

The ornamental design for a child's vehicle, substantially as shown.
